UNITED STATES PATENT OFFICE.

WILSON I. BLACK, OF MARION, OHIO.

STEEL TIE AND RAIL-FASTENER.

1,264,001.

Specification of Letters Patent. Patented Apr. 23, 1918.

Application filed November 13, 1917. Serial No. 201,810.

To all whom it may concern:

Be it known that I, WILSON I. BLACK, a citizen of the United States, residing at Marion, in the county of Marion and State of Ohio, have invented certain new and useful Improvements in Steel Ties and Rail-Fasteners; and I do hereby declare the following to be a full, clear, and exact description of the invention, such as will enable others skilled in the art to which it appertains to make and use the same.

This invention relates to metallic ties and fasteners and the primary object of the invention is to provide an improved metallic tie, which will effectively take the place of the ordinary wooden ties and which has an improved means for holding the rails in position on the tie and preventing the same from spreading.

Another object of the invention is to provide an improved metallic tie having a block of asphaltum inserted therein to form a seat, so that the asphaltum will effectively absorb the shocks transmitted through the rails and reduce the noise and clatter usually associated with metallic articles.

A further object of the invention is to provide a pair of arms pivotally carried by the upper surface of the tie for engaging the opposite sides of a rail, said members having means to hold the same in engagement with the rail and thus absolutely prevent any movement of the rail in relation to the tie.

A still further object of the invention is to provide an improved metallic tie and fastener of the above character, which is durable and efficient in use, one that is simple and easy to manufacture, and one that can be placed upon the market at a reasonable price.

With these and other objects in view, the invention consists in the novel construction, arrangement and formation of parts, as will be hereinafter more specifically described, claimed and illustrated in the accompanying drawings, forming a part thereof in which:

Figure 1 is a side elevation of one end of the improved tie showing the same partly in section and a rail fitted thereon, and

Fig. 2 is a plan view of one end of the improved tie showing the rail in position.

Referring to the drawing in detail, where-
55 in similar reference numerals designate corresponding parts throughout the several

views, the numeral 1 generally indicates the improved tie, which is preferably formed of metal, such as steel or the like and has formed adjacent each end thereof on its upper surface a cut out portion or recess 2 in which is fitted a block of asphaltum 3. The upper edge of the asphaltum block 3 is fitted flush with the top of the tie 1 and the same acts as a seat for the metallic rails 4, which are laid on top of the same, and the asphaltum blocks effectively absorb the shock transmitted to the tie through the rails. The rails 4 are of the ordinary construction and include the head 5, the base 6 and the connecting flange 7. Secured on the upper surface of the tie and on each side of and in spaced relation to the asphaltum block 3 are brackets 8, each of which includes the base plate 9 and the spaced upwardly extending ears 10, which extend beyond the base plate and toward the asphaltum block. The base 9 is provided with a central aperture 11 which registers with a vertical aperture 12 formed in the tie 10 and these registering apertures receive a bolt 13 which has its lower end threaded. A nut 14 is threaded on the lower end of the same and holds the bolt in engagement with the bracket 8, which holds the same in position. A suitable washer 15 is positioned between the nut and the tie 1. The forwardly projecting portions of the ears 10 are provided with registering apertures, which receive a pivot bolt 16 which pivotally supports an arm 17. The arm 17 is substantially rectangular in form and is provided at its rear end with an opening which receives the pivot bolt 16. A suitable nut 18 is turned on the pivot bolt 16 and holds the same in position. The free ends of the arms 17 are each provided with inwardly inclined lower surfaces 19, which conform to the configuration of the base 6 of the rail 4. The inclined surfaces 19 of the free ends of the arms 10 end abruptly and extend downwardly as at 20 which provides shoulders for engaging the side edges of the base 6 of the rail 4 and thus prevent spreading of the rails. The arm 17 is provided with a vertical aperture 21 which registers with an aperture 22 formed in the asphaltum block and an aperture 23 formed in the tie and the registering apertures receive a suitable locking bolt 24, which has its upper end threaded and a suitable nut 25 turned on the same. The nut 25 holds the bolt in

position and serves to form tightening means for forcing the arms 17 in engagement with the base 6 of the rail. Suitable washers 26 are interposed between the arms 17 and the asphaltum block, and between the bolt head and the tie and the nut and the arm.

From the foregoing description it can be seen that an improved metallic tie is provided which carries means for engaging the rail, which absolutely prevent any spreading of the rail in relation to the tie.

While the drawings only show one end of the tie, it is to be understood that each end of the tie is to be constructed in duplicate. The means for holding the rail in position on the tie has been shown in connection with a metallic tie, but it is to be understood however that this fastening means can be effectively used in connection with the ordinary type of wooden tie.

In practice, I have found that the form of my invention, illustrated in the accompanying drawings and referred to in the above description, as the preferred embodiment, is the most efficient and practical; yet realizing the conditions concurrent with the adoption of my device will necessarily vary, I desire to emphasize the fact that

various minor changes in details of construction, proportion and arrangement of parts may be resorted to, when required, without sacrificing any of the advantages of my invention as set forth.

What is claimed as new is:—

1. In a device of the class described, a tie, spaced brackets secured to the upper surface of the tie, an arm pivotally secured to each bracket, the free ends of the arms having their lower surfaces beveled, and locking bolts extending through the tie and engaging the free ends of the arms for holding the same in a locked position.

2. In a device of the class described, a tie having a recess formed in its upper surface adjacent each end thereof, an asphaltum block positioned in said recess, pivoted arms carried by the upper surface of the tie, and means extending through the tie and the asphaltum block and the arms for holding the arms in locked position and the asphaltum block in said recess.

In testimony whereof I affix my signature in presence of two witnesses.

WILSON I. BLACK.
